UNITED STATES PATENT OFFICE.

LEWIS R. DAVIS, OF SAN FRANCISCO, CALIFORNIA.

FLEXIBLE SKIRT PISTON.

Application filed July 27, 1925. Serial No. 46,445.

This invention relates to pistons of the split skirt type especially those adaptable for internal explosive engines, and the objects of the invention are to provide a split 5 skirt piston construction which is easily produced by ordinary molding or die casting processes which will effect a perfect fit to the cylinder to compensate for considerable wear thereof, and which will greatly reduce 10 the oil pumping tendency common to such pistons. Other advantages of my construction will appear in the following description. The drawings accompanying this specification show the preferred embodiment 15 of the invention, it being understood that such minor changes as fall within the spirit thereof are intended to be covered in the claims hereto appended.

Figure 1 of the drawing is an external 20 view of my piston.

Figure 2 is a vertical section through the center thereof.

Figure 3 is a transverse section of the piston as taken along the line 3—3 of Figure 2.

In further detail my piston comprises a head 1 cast with a cylindrical wall 2, and a pair of opposed bosses 3 adapted to take the wrist pin 4 of a connecting rod 5.

The bosses 3 are rigidly braced to the wall and head by an integrally cast rib 6 extending across the under side of the head 1. The cylindrical wall 2 is of reduced diameter from its lower edge to a point 35 "A" above the bosses, and surrounding this reduced portion is an outer flexible wall or split skirt 7.

This skirt 7 is spaced from the reduced wall by an annular space 8 preferably 40 slightly larger at the bottom as indicated in Figure 2, so that in die casting the core die may be easily pulled out. The skirt is cast integrally with the body of the piston, being connected thereto by a lug 9 adjacent 45 which the skirt is slotted from end to end after finishing as shown at 10.

The lug 9 and slot 10 may be vertical but I prefer to run them on a spiral, as indicated in Figure 1, so that the skirt in expanding, to compensate for cylinder wear, 50 will better preserve its rotundity.

The lug 9 may be of any desired proportions and located directly at the point of slotting or spaced therefrom, or if desired 55 two lugs may be used and also two slots,

this all depending on the amount of flexibility desired in the particular piston.

In casting the piston and skirt the space 8 may terminate as indicated at 8' and the skirt is extended as indicated at 7' to connect integrally with the piston body, so that it forms a firm unit for turning, grinding or boring for the wrist pin, etc., after which two oil ring grooves 11 are turned in the upper end of the piston and finally a third 65 groove 12 which penetrates the cored space 8' and separates the upper end of the skirt from the body of the piston.

The skirt is bored at 15 to clear the pin 4 so that the skirt will be free to expand 70 against the cylinder walls, and just below the bosses 3 a split expanding or bull ring 13 is seated in a very shallow groove 14 turned in the inner surface of the skirt.

In using the piston the usual split rings 75 are inserted in the grooves 11 and 12 and a ring in the latter, it will be noted, will be supported between an upper wall formed on the body of the piston and the substantially free upper end of the skirt. This construction provides a flexible skirt supporting the lower ring and with a free annular passage 8 extending from the skirt and body of the piston open at almost the entire circumference of the piston to the lower oil ring 85 groove. Thus, the annular passageway 8 functions to completely drain any surplus oil from the lower groove back into the crank case, and the reduced diameter of the piston body acts as a baffle wall to prevent 90 oil being thrown into the passageway, and the bull ring positioned to almost cover the lower end of the passageway prevents any oil being thrown upwardly into the passage, thus insuring that the oil will not rise 95 in injurious amount above the lower ring, and the skirt itself being split from end to end and spaced from the body of the piston acts like a very long ring almost independent of the body, thus effectually compensating 100 for all wear of the walls.

I claim:

1. A piston comprising a head portion having a reduced lower end of annular cross-section throughout, the said reduced lower end being bored at opposite points above its lower edge to provide wrist pin bosses, a split skirt surrounding the said reduced lower end portion and extending 105 above the wrist pin bosses and a rib con- 110

nected to the reduced lower end portion and to the skirt for supporting the latter in spaced relation to the head and to the said lower end portion.

5. 2. A piston comprising a head, a split skirt located below the head and spaced therefrom, the said head having a reduced lower end portion of annular cross-section extending into the upper end of the skirt
10 and downwardly therethrough and spaced therefrom and operating to provide a baffle for intercepting lubricant entering upwardly through the lower end of the skirt and directing the lubricant inwardly and away
15 from the adjacent intervening space, said reduced lower end portion having oppositely disposed wrist pin bosses located below the upper end of the skirt, a rib connected to the said lower end portion of the head and to the skirt and for supporting the latter in spaced relation to the head and to the said reduced end portion thereof, and
20 a ring interposed between the said reduced lower end portion of the piston and the lower end portion of the skirt and overlapping the intervening space between the skirt and the lower end portion for the purpose described.
3. A piston comprising a head, a split skirt located below the head and spaced
25 therefrom, the said head having a reduced lower end portion of annular cross-section extending into the upper end of the skirt and downwardly therethrough and spaced

therefrom and operating to provide a baffle for intercepting lubricant entering upwardly through the lower end of the skirt and directing the lubricant inwardly and away from the adjacent intervening space, said reduced lower end portion having oppositely disposed wrist pin bosses located below the upper end of the skirt, a rib connected to the said lower end portion of the head and to the skirt and for supporting the latter in spaced relation to the head and to the said reduced end portion thereof, and
40 a ring interposed between the said reduced lower end portion of the piston and the lower end portion of the skirt and overlapping the intervening space between the skirt and the lower end portion for the purpose described.

4. A piston comprising an upper or body portion supporting bosses bored for the wrist pin, and a flexible split sleeve or skirt surrounding the lower part of the body portion and spaced therefrom, said sleeve being split from end to end along a spiral line and integrally connected to the lower part of the body portion by a cast spiral lug lying adjacent one edge of the split.
